UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO.

MANIFOLDING SALES-BOOK.

1,305,056.

Specification of Letters Patent. Patented May 27, 1919.

Application filed October 10, 1917. Serial No. 195,681.

To all whom it may concern:

Be it known that I, EDWARD KIRBY BOTTLE, a citizen of the United States, residing at Elmira, in the county of Chemung and 5 State of New York, have invented certain new and useful Improvements in Manifolding Sales-Books, of which the following is a full, clear, and exact description, such as will enable others skilled in the art to which it 10 appertains to make and use the same.

This invention relates to manifolding devices and with regard to its more specific features to manifolding salesbooks.

An object of this invention is to provide a 15 salesbook with which a greater number of copies of a portion of a record may be made than of other portions in a practical and economical manner.

A further object is to provide a device of 20 the character described which will be simple and practical in operation and economical to manufacture.

Other objects will be in part obvious and in part pointed out hereinafter.

In the accompanying drawings forming 25 part of this specification wherein similar reference characters refer to similar parts throughout the several views,

Figure 1 is a perspective view of a salesbook embodying this invention;

Fig. 2 is a side elevation partly sectional showing diagrammatically the arrangement of the leaves of the book;

Fig. 3 is a fragmental view showing a 30 modified form; and

Fig. 4 is a fragmental view showing another modification.

In the drawings there is provided as at 1, 35 a pad of sheets, each sheet being folded upon itself to form two superposed leaves; an original or free leaf 2 and a duplicate or bound leaf 3.

In manifolding salesbooks, it is frequently required that only a portion of the record 40 shall have a multiple copy made thereon. A practical manner of meeting conditions is to cause a portion of the record surface of one of the leaves to extend out beyond the other of the leaves, which portion is adapted 45 to have inscribed thereon only that portion of the record of which a multiple copy is not desired.

As illustrated in the accompanying drawings, the original or free record leaf 2, of 50 each of the sheets of the pad 1, does not

cover the entire record surface of the duplicate or bound record leaf 3, but is of a size to expose the portion of the companion duplicate leaf adjacent the bound end of the leaf, being shorter than the leaf 3, to leave 60 a portion 10 of the record surface of the leaf 3 exposed beneath the leaf 2.

Should it be desired to make a triplicate copy of the record appearing on the leaf 2, there is attached to the pad 1 a support 4 65 on which may be provided a triplicating pad 5 in position to have its leaves inserted between the leaves of the top sheet 2 of the pad 1 and these leaves will ordinarily be only of such size as to expose the portion 10 70 of the leaves 3. In order to provide a convenient means for disposing of the triplicate leaves 5 after the inscriptions are made thereon, the support 4 may comprise two hinged members 6 and 7 forming between 75 them a receptacle in which the leaves 5, which have received their inscription, may be inserted.

In order to cause the transfer of the records made upon the sheet to the triplicate leaf 5 and to the duplicate leaf 3, a sheet of double-faced transfer material as a carbon sheet 8, is provided, and this sheet will be so disposed as to lie over that portion of the leaf 3 which has the leaf 2 superposed thereon. Also the triplicating leaves are of such 85 size as to expose the portions of the transfer sheet opposite the exposed portion of the duplicate leaves.

A means for positioning the sheet 8 will be 90 provided such that while firmly holding the transfer sheet in position for use beneath the free leaf 2, it will afford a clean support and outer surface of the book for the hand while the manipulator is making a record upon the original leaf 2, and at the same time enable 95 a record to be made upon the portion 10 of the duplicate leaf 3 either directly or through the medium of transfer material.

A practical device for positioning the sheet 100 of transfer material beneath the free leaf of the pad 1 is the provision of a means for connecting the transfer sheet to the bound end of the pad, which means will be preferably bound in the pad by staples 9. In the embodiment illustrated in the drawings, the attaching or connecting means comprises 105 an extended portion of the transfer sheet which is bound to the pad. If the extended portion of the carbon sheet is double faced 110

with transfer material, the attaching means will further comprise a protector 13 which will cover the exposed portions of the carbon surface to prevent the hands being smutted thereby when the book is used.

This attaching means will be arranged so as to permit a record to be made upon the portion 10 of the record surface of the sheet 3. If, however, the extended portion of the 10 carbon sheet be of a material having no carbon surface, as in the form illustrated in Fig. 4, no separate protector 13 will be required. This form of the device may be conveniently constructed either by removing 15 the transfer material from the upper surface of an extended portion of the transfer sheet or by using a separate sheet having no transfer material, to which the transfer sheet 8 may be attached.

20 In the form illustrated in Figs. 1, 2, and 4, an opening 11 is cut in the portion 10^a of the transfer sheet in position to expose that portion of the record surface 10 upon which it is desired to make the independent 25 record, and in the form illustrated in Fig. 1 a corresponding opening 14 will be cut through the protector 13 so that an inscription may be made directly upon the record surface 10 with the pencil.

30 In the form illustrated in Fig. 3, however, no opening is cut in the extended portion of the transfer sheet or in the protector. The inscription may be written directly upon the protector and transferred to the exposed 35 portion of the record sheet by means of the extended portion of the transfer sheet.

In order to permit the ready removal of the original leaf of the upper sheet of the pad 1, from beneath the sheet of transfer material, a suitable notch as 15 will be provided in the transfer sheet, if required, in the protector 13, in position to expose a corner of the original leaf of the top sheet. The manipulation of the book is as follows:

45 In order to set the book with the leaves in the position illustrated in Fig. 1, so as to be ready to have a record made therein, the corner of the original leaf of the top sheet is grasped at the point where it is exposed by the notch 15 and removed from beneath the transfer sheet. Thereupon the back leaf of the triplicating pad is superposed upon the transfer sheet and the original leaf superposed thereon. The book is now in position 50 to have a record made, and any record which is inscribed upon the original leaf 2 will be transferred to the triplicate leaf 5 and to the duplicate leaf 3 by means of the upper and lower faces of the transfer sheet respectively. That portion of the record which it is desired to have appear only on the duplicate leaf will be inscribed upon the portion 10 of the surface of the duplicate leaf through the openings 14 and 11 in the modification shown in Figs. 1, 2 and 4, and di-

rectly upon the surface of the support 13 in the modification shown in Fig. 3.

Thereafter the triplicate leaf 5 upon which the record has been made may be inserted 70 between the supports 6 and 7 and the leaves 2 and 3 removed. The record upon the leaf 3 will contain, in addition to the matter recorded upon the leaves 2 and 5, the matter which was inscribed upon the portion 10 of the leaf 3.

75 In cases where it is not desired that a triplicate copy of the record shall be made, a practical, efficient and satisfactory book for making duplicate copies may be provided by omitting the pad 5 of triplicate leaves. Under such circumstances, the transfer sheets may be single faced, if desired, in which case the modification illustrated in Fig. 4 will prove economical as under such circumstances there would be no necessity of 80 removing carbon from the upper face.

Thus by the above construction are accomplished, among others, the objects hereinbefore set forth.

As many changes could be made in the 90 above construction, and many apparently widely different embodiments of this invention could be made without departing from the scope thereof, it is intended that all matter contained in the above description or 95 shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween. 100

Having described my invention, what I claim as new and desire to secure by Letters Patent is:

1. A manifolding sales book comprising, in combination, a pad of original and duplicate record leaves, the originals being of a size to expose a portion of the companion duplicate leaves when in superposed relation, a sheet adapted to lie between the uppermost original and duplicate leaves of the 110 pad and over said exposed portion of the duplicate leaves, said sheet being provided with transfer material on the portion between said leaves and with an opening through which inscription may be made on 115 said exposed leaf portion.

2. A manifolding sales book comprising, in combination, a pad of original and duplicate record leaves, the originals being of a size to expose a portion of the companion 125 duplicates leaves when in superposed relation, a sheet adapted to lie between the uppermost original and duplicate leaves of the pad and over said exposed portion of the duplicate leaves, said sheet being provided 130

with transfer material on the portion between said leaves and with an opening through which inscription may be made on said exposed leaf portion, said book including a clean outer sheet surface opposite said exposed leaf portion.

3. A manifolding sales book comprising, in combination, a pad of original and duplicate record leaves, a sheet of transfer material adapted to transfer impressions from an original to a duplicate leaf, the original leaves of the pad being of a size to expose a portion of the companion duplicate leaves, when in superposed relation one to another, the transfer sheet being of a size to lie on the exposed portion of the duplicate leaf, and having an opening opposite a record portion of the duplicate leaves through which inscription may be effected, and a protector leaf lying over said transfer sheet opposite said exposed portion of said duplicate leaves, and having an opening in line with the opening in said transfer sheet.

4. A manifolding sales book comprising, in combination, a pad of original and duplicate record leaves, a sheet of transfer material adapted to transfer impressions from an original to a duplicate leaf, the original leaves of the pad being of a size to expose a portion of the companion duplicate leaves, when in superposed relation one to another, the transfer sheet being of a size to lie on the exposed portion of the duplicate leaf, a second pad the leaves of which are adapted

to be interposed between said transfer sheet and one of said record leaves, the leaves of the second pad exposing a portion of the transfer sheet opposite the exposed portion of the duplicate leaves, and a protector leaf lying over said transfer sheet opposite said exposed portion of said duplicate leaves.

5. A manifolding sales book comprising, in combination, a pad of original and duplicate record leaves, a sheet of transfer material adapted to transfer impressions from an original to a duplicate leaf, the original leaves of the pad being of a size to expose a portion of the companion duplicate leaves, when in superposed relation one to another, the transfer sheet being of a size to lie on the exposed portion of the duplicate leaf, a second pad the leaves of which are adapted to be interposed between said transfer sheet and one of said record leaves, the leaves of the second pad exposing a portion of the transfer sheet opposite the exposed portion of the duplicate leaves, and a protector leaf lying over said transfer sheet opposite said exposed portion of said duplicate leaves, and in non-overlapping relation to the interposed leaf of said second pad.

In testimony whereof I affix my signature in the presence of two witnesses.

EDWARD KIRBY BOTTLE.
